UNITED STATES PATENT OFFICE

SEYMOUR B. DEWEY, JR., OF CLEVELAND, OHIO, ASSIGNOR TO THOMAS H. TAYLOR, OF
EAST MCKEEPSPOET, PENNSYLVANIA

PROCESS OF MAKING CLEANING COMPOUNDS

No Drawing.

Application filed December 24, 1926. Serial No. 157,000.

This invention relates to cleaning compounds for floors, woodwork and the like and more particularly to the process of making the cleaning compound.

5 An object of my invention is to provide a process of making such a cleaning compound which is particularly effective for cleaning linoleum, rubber, marble and other kinds of floors, painted or varnished woodwork and 10 the like.

Another object of my invention is to provide a process of making a cleaning compound which contains a minimum amount of free alkali so that the compound will not be injurious to the human skin or to the article 15 being cleaned.

A further object of my invention is to provide a process of making a mild liquid soap having valuable detergent and germicidal 20 properties, and which is readily miscible with water to form a smooth soap solution of any desired concentration.

Other objects of my invention will be apparent to those skilled in the art from the description of it hereinafter given.

The preferred form of soap is prepared from raw linseed oil saponified with potassium hydroxide. It has been found that 30 potassium hydroxide produces a softer, more smooth soap and emulsion without the liability of forming curds or scums.

Castor oil may also be present in the cleaning compound and the castor oil may either be substantially all saponified or partly 35 saponified and partly in an unsaponified emulsion. A saponified castor oil is not only a detergent and a solvent, but has very valuable preservative and germicidal properties.

Linseed oil is advantageous in that it 40 acts readily with the saponifying agent to form a smooth soap having excellent detergent qualities. While cotton seed oil might in certain cases be employed in place of linseed oil, I greatly prefer linseed oil as the 45 main ingredient of my soap.

Castor oil in its saponified condition imparts not only detergent qualities to the soap, but also extremely valuable preservative and germicidal properties. Thus, it is now known that castor oil soap has a higher germicidal value than carbolic acid. The amount of saponified castor oil in the soap will, of course, depend on the characteristics desired in the finished soap. Unsaponified castor oil may be present in the soap to advantage, whereby an extremely thin film of oil may remain on the surface to be cleaned. This feature is particularly desirable when the soap is used, for example, in cleaning articles where an excellent finish is desired, such as, fine woodwork, furniture and even some kinds of floors.

I prefer in the manufacture of my soap to permit any glycerin formed to remain in the soap, thereby adding a soothing effect when the soap comes in contact with the human skin.

In the manufacture of my improved soap, caustic potash preferably of relatively high purity is used to saponify the linseed oil or 70 other oil from which the soap is being formed. We have found that a very desirable way of carrying out the saponification is to heat the oil, such as linseed oil, with substantially equal amounts of water substantially to the 75 boiling point, and separately dissolve the potassium hydroxide in water, to form a concentrated solution. The potassium hydroxide solution is then heated if necessary to bring it to substantially the same temperature as the hot oil and water, and is added in successive increments to the oil and water.

Upon thorough mixing of the oil and potassium hydroxide, heating is continued until the mixture boils for some time and the saponification reaction has taken place in the solution. Cold water is then added in substantial quantities together with constant stirring, and this seems to cause formation of a gel of the soap and produces a very homo- 80 85 90

geneous solution of the soap. The smoothness and solubility of the soap solution in water may even be further increased by permitting the mixture to age for from 1 to

5 7 days and then diluting to the proper amount to obtain the desired concentration and consistency.

Preferably sufficient potassium hydroxide is used to give an excess of alkali to the mixture, and after the saponification reaction and the addition of the cold water a small amount of castor oil may be added depending upon the desired composition of the resulting compound. The castor oil is preferably added 10 in sufficient quantity to be partly saponified by the free alkali, and the remaining portion of the castor oil forms an unsaponified emulsion of castor oil in excess of the amount required to react with the free alkali.

15 20 For cleaning purposes the amount of castor oil added is preferably about 1% of the soap solution, but if it be desired to have the soap solution more germicidal or to have more unsaponified castor oil in emulsion, more castor oil may be used.

25 The percentage of castor oil may be as great as from 5% to 10% if desired, and by controlling the amount of potassium hydroxide used such castor oil may be completely saponified or partially saponified, leaving the balance as an unsaponified emulsion of castor oil.

30 35 The unsaponified castor oil or other oil present in the soap solution forms a thin film of oil on the surface being cleaned. It is obvious, therefore, that the desired film of oil may be controlled by controlling the amount of unsaponified emulsion of oil present in the liquid soap and by the selection of an oil which has in relatively high degree the property of spreading on and adhering to the surface.

40 It is preferred to use caustic potash to cause saponification because this produces a softer, smoother soap which has a lower melting point and is liquid under ordinary conditions, and also has a greater solubility. The addition of the cold water mentioned above results in the gelatinization or thickening of the potassium soap. The soap is quite hygroscopic and takes up water freely, and this property is taken advantage of to produce a very smooth liquid soap which may be readily mixed with water to the desired consistency.

45 55 The cleaning compound may be concentrated to form a thin liquid or even further concentrated to form a gel or paste, and this latter is also readily miscible with water. If the concentration is carried to the point of 60 forming a paste or gel, the material obviously contains less water and can be readily shipped in this concentrated form with a saving in transportation cost. It is also less subject to freezing during shipment when in this form 65 and may be more advantageous for use for

various purposes. It may be noted, however, that freezing and thawing does not seem to injure the liquid soap product produced by my process.

It will furthermore be noted that I prefer 70 to permit any glycerin formed during the saponification to remain in the soap. As has been previously mentioned, the presence of glycerin is advantageous when the soap comes in contact with the human skin.

75 It may also be noted that pine oil or sassafras oil or any other suitable oils to provide the desired odor to the resulting soap may be used. If pine oil is used it also adds to the cleaning properties of the soap compound.

80 It will be understood that certain ingredients mentioned above may be omitted from my improved soap while yet retaining many of the advantages of my invention.

85 Furthermore, it is to be understood that the particular compounds disclosed, and the procedure set forth, are presented for purposes of explanation and illustration and that various equivalents can be used and modifications of said procedure can be made without departing from my invention as defined in the appended claims.

What I claim is:

1. The process of making a cleaning compound which comprises heating linseed oil 95 with water, adding potassium hydroxide in excess of that required to saponify the oil, boiling the mixture until saponification is substantially complete, adding cold water to cause gelatinization of the soap solution, adding castor oil in a quantity in excess of that required to react with the free potassium hydroxide, heating the mixture and thereby saponifying a portion of the castor oil and forming an emulsion of unsaponified oil. 100 105

2. The process of making a cleaning compound, which consists in heating linseed oil and water, adding successive increments of potassium hydroxide to saponify the oil, boiling the mixture until saponification is substantially complete, adding a sufficient quantity of cold water to the hot soap solution to cause the same to gel, adding castor oil, and emulsifying the castor oil in the soap solution to form a homogeneous cleaning compound. 110 115

3. The process of making a cleaning compound, which consists in heating linseed oil and water, adding successive increments of potassium hydroxide to saponify the oil, boiling the mixture until saponification is substantially complete, adding a sufficient quantity of cold water to the hot soap solution to cause the same to gel, adding castor oil, emulsifying the castor oil in the soap solution, and permitting the resulting soap solution to age. 120 125

4. The process of making a cleaning compound, which consists in heating linseed oil and water to approximately the boiling point of the mixture, dissolving potassium hydroxide in water and heating the same to substan- 130

tially the same temperature as the linseed oil mixture, adding said hot potassium hydroxide solution in successive increments to the linseed oil mixture to saponify said oil, boiling the mixture until saponification is substantially complete, adding a sufficient quantity of cold water to the soap solution while constantly stirring said soap solution to cause gelatinization thereof, adding castor oil, emulsifying the castor oil with the soap solution, permitting the resulting soap solution to age, and subsequently diluting the soap solution with the water to the desired consistency.

In testimony whereof I affix my signature.
